UNITED STATES PATENT OFFICE.

EDWIN NORTON, OF CHICAGO, ILLINOIS.

CAN.

SPECIFICATION forming part of Letters Patent No. 269,698, dated December 26, 1882.

Application filed November 23, 1882. (No model.)

To all whom it may concern:

Be it known that I, EDWIN NORTON, a citizen of the United States, residing in Chicago, in the county of Cook and State of Illinois, 5 have invented a new and useful Improvement in Cans, of which the following is a specification.

The present invention relates to improvements in open-mouthed sheet-metal cans, 10 wherein the cover is designed to be secured to the can by coupling devices which operate with a rotary motion, and more particularly to improvements upon the can for which a patent, No. 235,278, was heretofore granted to me under date of December 7, 1880.

In the present invention the seamless band or ring is provided with an inturned flange at each edge, which not only gives a stronger and firmer construction to the seamless ring, but 20 renders it unnecessary to secure it to the can-body at more than one edge, thus saving the soldering of one seam and materially lessening the cost as well as producing a better can.

In the accompanying drawings, which form 25 a part of this specification, and in which similar letters of reference indicate like parts, Figure 1 is a side elevation of a can embodying my invention. Fig. 2 shows the seamless ring before being secured to the can-body. Fig. 3 30 is a section showing cover removed, and Fig. 4 is a section showing cover applied.

In the drawings, A represents the can-body, preferably provided with an offset or shoulder, a, at its top edge.

35 B is the seamless band or ring. It is provided with an inturned flange at each edge b and b'. The upper flange, b, has its edge turned down to form a shoulder, b², which fits inside the can-body, and is secured or soldered there- 40 to.

C is the can cover. The cover C and the seamless ring or band B are both stamped out by dies, so that they of course accurately fit each other, and they are provided with suit-

able coupling devices, c and c', for securing 45 the cover tight upon the can. To insure a tight joint, a paper or other gasket, d, if desired, may be interposed between the cover and the top of the seamless ring. The cover C is provided with a circular recess or depression, d', in which the gasket fits, and which 50 also serves to strengthen the cover.

The strengthening-flange b' at the lower edge of the depending seamless ring may, if preferred, be turned outward or formed into a hollow bead or imitation wire; or this strengthening-flange may be omitted.

By using a depending seamless ring instead of soldering the seamless ring at both its upper and lower edge, as shown in my former 60 patent above referred to, while the seamless ring itself is made firm and strong by reason of the inturned flange, it nevertheless has a certain amount of elasticity, owing to the fact of its being secured to the can-body only at its 65 upper edge, which produces an easier, better, and closer fit with the can-cover than if it is rigidly soldered to the can-body at both edges, and in this way I also avoid all danger of irregularities in the fit of the can-cover and 70 seamless ring occasioned by irregularities in soldering the lower edge of the seamless ring rigidly to the can-body.

I claim—

1. The combination, with a can-body, of a 75 seamless ring or breast secured thereto, and provided with an inturned flange at each edge, substantially as specified.

2. The combination, with a can-body, of a depending seamless ring having an inturned 80 flange at the top, joined to the can-body, and a cover, said cover and seamless ring being provided with coupling devices, substantially as specified.

EDWIN NORTON.
